UNITED STATES PATENT OFFICE.

JOSEPH L. BARTH, OF BISMARCK, NORTH DAKOTA.

PEDOGRAPH AND METATARSAL-PAD LOCATOR.

Application filed July 22, 1926 Serial No. 124,229.

This invention relates to improvements in pedo-graphs or devices for taking foot impressions for use as a guide in the manufacture and fitting of footwear, and more particularly to improvements in a well known device of this character which embodies a plate upon which is placed a sheet of paper to receive the foot impression, and an ink carrying member adapted to be positioned over the impression receiving sheet when the foot impression is to be taken.

The present invention has for one of its objects to improve this device to the end that it may also be used for taking the impression of the arch of the foot for use as a guide in the placing of a metatarsal pad in the shoe.

With the foregoing and other objects in view, the nature of which will become apparent as the description proceeds, the invention consists of the novel construction, combination and arrangement of parts hereinafter fully described and claimed, and illustrated in the accompanying drawings, wherein:

25 Figure 1 is a top plan view of the pedograph embodying my invention, the device being shown adapted for the purpose of taking foot impressions,

Figure 2 is a view in front elevation of the 30 device,

Figure 3 is a view similar to Figure 1 showing the device adapted for the purpose of taking the impression of the arch of the foot,

35 Figure 4 is a transverse sectional view taken on the vertical plane indicated by the line 4—4 of Figure 1,

Figure 5 is a longitudinal sectional view taken on the vertical plane indicated by the 40 line 5—5 of Figure 3,

Figure 6 is a transverse sectional view taken on the vertical plane indicated by the line 6—6 of Figure 3, and

Figure 7 is a detail sectional view taken 45 on the vertical plane indicated by the line 7—7 of Figure 3.

Corresponding and like parts are referred to in the following description, and designated in the several views of the accompanying drawings, by similar reference characters.

The pedo-graph comprises, as shown in the drawings, a shallow receptacle 1. The upper side of the front portion 1^a of the receptacle 1 is fully open, and the rear portion 55 of the receptacle is formed to provide a housing 1^b. A plate 2 upon which is placed the

sheet of paper to receive the foot impression, is arranged within the receptacle portion 1^a. A spring pressed roller, not shown, upon which is wound an ink carrying member 3, is journaled within the housing 1^b. The ink carrying member 3 passes through an opening 4 in the front side of the housing 1^b, and located within the opening and below the ink carrying member is an inking device 5, of well known construction, for applying ink to said member as it is unwound from the spring pressed roller to which it is secured. A bail 6 which is connected to the front edge of the ink carrying member 3 and pivotally secured as at 7 to the ends of the receptacle portion 1^a, provides means for limiting the extent to which said member may be wound on the spring pressed roller and for holding said member against the tension of said roller over the plate 2 when the impression of a foot is being taken. A pull 8 is secured to the front end of the ink carrying member 3 to permit said member to be readily extended over the plate 2 and to also permit the bail 6 to be lifted when it is desired to permit said member to be rewound by and on the spring pressed roller. A heel plate or rest 9 is removably positioned in a slot 10.

In accordance with the present invention, 85 the plate 2 is made in two parts or sections 2^a and 2^b. The plate section 2^a is permanently fixed within the receptacle portion 1^a, and the plate section 2^b is slidably supported by guides 12 for movement towards and from 90 the plate section 2^a. The plate sections 2^a and 2^b rest upon blocks 12^a and 12^b, respectively, which are relatively spaced and secured within the receptacle portion 1^a between the guides 12. The plate section 2^a 95 and the block 12^a are spaced from the adjacent end wall of the receptacle portion 1^a to provide the heel plate receiving slot 10. The heel plate 9 rests upon the bottom of the receptacle portion 1^a, and it is removably supported in upright position thereon by the plate section 2^a, block 12^a and adjacent end wall of this receptacle portion. The outer end of the plate section 2^b is provided with a notched lug 13 which is adapted to be used 100 for and when adjusting this plate section with respect to the plate section 2^a. The lug 13 projects beyond the adjacent end of the receptacle portion 1^a, and said end of said portion is provided with an opening 14 for the reception of the plate section 2^b. The adjacent ends of the plate sections 2^a and 2^b 105

have bevelled under sides 15 and 16, respectively. A spring plate 17 is secured within the receptacle portion 1^a beneath the plate 2 and between the blocks 12^a and 12^b, and is exposed or presented for use only when the plate section 2^b is drawn outwardly or adjusted in a direction away from the plate section 2^a. A greater or lesser portion of the spring plate 17 may be exposed or presented for use by adjusting the plate section 2^b in a direction away from the plate section 2^a for different distances, and the extent of such adjustment of the plate section 2^b will depend solely upon the length of the foot of which the impression of the arch is to be taken. To enable the accurate adjustment of the plate section 2^b the front upper edge of the receptacle portion 1^a is provided with a scale 18. After the plate section 2^b has been adjusted, the exposed portion of the spring plate 17 is arched or bowed upwardly above the plate sections 2^a and 2^b by a cam 19. This part is located below the spring plate 17 between the guides 12, and is carried by a shaft 20 which is slidably and rotatably supported by the guides 12 and to the outer end of which a lever 21 is secured. A plate 22 is secured to the front side of the receptacle portion 1^a and is provided with an arcuate series of openings 23. A bolt 24 fixed to the handle 21 and provided with a knob 25, is adapted, as the shaft 20 is slidably as well as rotatably supported, to be arranged in any of the openings 23 in the plate 22 to secure the cam 19 in adjusted position against casual movement. The cam 19 normally occupies an inactive position, in which position thereof it is out of contact with the spring plate 17, and it may be swung through any angle from this position through the medium of the knob 25, the extent of the adjustment of the cam 19 depending solely upon the arch or bow it is desired to impart to the spring plate 17. The beveled ends 15 and 16 of the plate sections 2^a and 2^b permit the ready adjustment of the latter section.

To use device to measure the foot for shoe size or to diagnose the various forms of foot ailments, it is used with plate 2^b shoved in until it comes in contact with 2^a, which forms a flat base over which a sheet of paper 26 with a standard foot measuring scale printed on the upper side is placed. Thereafter the ink carrying member 3 is adjusted or extended over the sheet of paper 26. The placing of the foot upon the ink carrying member 3 will result in an impression of the foot being made on the paper over a flat surface.

To use for locating the position in the shoe where the metatarsal pad should be placed, plate 2^b is drawn back away from plate 2^a until its edge 16, is in line with the number on scale 18 to correspond with the size of shoe into which the pad is to be built. The cam 19 is next adjusted to arch or bow the spring

plate 17 upward between plates 2^a and 2^b to a height to correspond with the height of the arch of the shoe into which the pad is to be built. Thereafter the ink carrying member 3 is extended over the sheet of paper 26. The foot is placed upon the ink carrying member 3 directly over the arched plate 17. Heel plate 9 is then removed from its normal position and used as a guide to mark the position of the back of the heel on the paper 26. The impression thus made on the paper 26 will show the length of the foot and the position of the arch therein, and from this data the point at which the arch should be located in the shoe may be readily determined.

To use the device for making shoes to order for either crippled or normal feet, the size is first determined as hereinbefore explained; the plate 2^b is then drawn back away from 2^a until its edge 16 is in line with the number on the scale 18 corresponding with the size determined, and the foot is then placed over spring plate 17. The cam 19 is next adjusted to raise spring plate 17 to come in contact with the arch of the foot firmly enough to give the desired shank support. The foot is then removed and paper 26 is placed over spring plate 17. Also ink carrying member is brought forward to extend over paper 26. The foot is placed upon the ink carrying member 3 and a mark made to determine the back of the heel will result in the impression of the foot. Thus it is possible to make the depressions and raises in the insoles of the shoes under construction fit the sole of either a crippled or a normal foot.

It should be understood that the drawings are merely illustrative and do not pretend to give exact proportions. Furthermore, the said drawings are illustrative of a preferred construction, it being my expectation that various changes and modifications may be made without departing from the spirit and scope of my invention.

What is claimed is:

1. A device of the character set forth, including a plate upon which the foot is adapted to be placed and embodying sections adjustable relatively to provide an opening in the plate in registration with the arch of the foot, a flexible plate located below said first plate, and means for bowing the flexible plate upwardly through the opening and into contact with the arch of the foot.

2. A device of the character set forth, including a plate upon which the foot is adapted to be placed and embodying sections adjustable relatively to provide an opening in the plate in registration with the arch of the foot, a flexible plate located below said first plate, a cam adjustable for bowing the flexible plate upwardly through the opening and into contact with the arch of the foot, and means for securing the cam in adjusted position.

3. A device of the character set forth, including a plate upon which the foot is adapted to be placed and embodying sections adjustable relatively to provide an opening in the plate in registration with the arch of the foot, a flexible plate located below said first plate, a shaft slidably and rotatably mounted, a cam carried by the shaft for bowing the flexible plate upwardly through the opening and into contact with the arch of the foot, a lever secured to the shaft, a plate provided with an arcuate series of openings, and a bolt secured to the lever and adapted to engage in one of the openings in said last plate to secure the cam in adjusted position.
4. A device of the character set forth, including a plate upon which the foot is adapted to be placed and embodying sections adjustable relatively to provide an opening in the plate in registration with the arch of the foot, a flexible plate located below said first plate, and means for bowing the flexible plate
- 5 upwardly through the opening and into contact with the arch of the foot, the adjacent ends of the sections of said first plate having beveled under sides with which the flexible plate contacts.
5. A device of the character set forth, including a receptacle provided with guides, a plate upon which the foot is adapted to be placed and embodying sections, one of said sections being fixed within the receptacle in alinement with the guides, the other section being slidably mounted in the guides for adjustment with respect to the fixed section to provide an opening in the plate in alinement with the arch of the foot, a spring plate mounted within the receptacle below said first plate, and means for bowing the flexible plate upwardly through the opening and into contact with the arch of the foot.

In testimony whereof I affix my signature.

JOSEPH L. BARTH.
